UNITED STATES PATENT OFFICE.

PHILIP POORE, OF LONDON, ENGLAND.

APPARATUS FOR TREATING SUBSTANCES IN A FINELY-DIVIDED CONDITION.

1,420,944.

Specification of Letters Patent. Patented June 27, 1922.

Application filed April 13, 1920. Serial No. 373,602.

To all whom it may concern:

Be it known that I, PHILIP POORE, a subject of the King of Great Britain and Ireland, residing at 1/4 Paternoster Row, London, E. C., England, have invented certain new and useful improvements relating to apparatus for treating substances in a finely-divided condition or for carrying out processes in the use of materials in a finely-divided condition, of which the following is a specification.

This invention relates to apparatus for treating substances in a finely divided condition or for carrying out processes in the use of materials in a finely divided condition. It is applicable for example to apparatus for the carbonization of saw-dust or for carbonizing other carbonaceous materials in a finely divided condition. It is also applicable in the treatment of vapours or gases with substances in a finely divided condition. It is also applicable for example to a lime purifier or in fact for any purpose or process where contact is required between fluids and solids in a finely divided condition.

One of the objects of the invention is to utilize a rotating casing conveniently of cylindrical form in which the material to be treated, or the material used in the treatment, is charged, and according to the invention a flue or flues is or are provided within this rotating casing, and these flues are so constructed that while the vapour or gas may pass into the flue or flues from within the casing or into the casing from the flue or flues or both, according to the character of the treatment being carried out, the material treated or used in the treatment is, notwithstanding that it is in a finely divided condition, prevented from passing into the flue so as to accumulate therein, while yet free ingress and egress is permitted to the vapour or gas.

According to the invention the flue or flues is or are provided with annular or other shaped pockets so formed that there is free communication for a fluid such as vapour or gas to pass through the pockets, but any solid matter such as the finely divided substance treated or used in the treatment, is intercepted within the annular or other shaped pocket and prevented from accumulating in the flue.

According to one modification of the in-

vention the intercepting annular pockets are each formed of two walls and as these annular pockets are disposed adjacent each other, the walls of the series of pockets thus form an outer and inner wall for the flue. The outer wall of each pocket is provided of a ridge form and a hole or holes is or are provided at the summit of the ridge, so that thus, should any of the finely divided material fall into the pocket in one position in the rotation of the casing, it may readily fall out in other positions by reason of the downwardly inclined or ridge formation of the outer wall of the pocket. The hole at the ridge may advantageously be a circular or annular slot extending completely around the outer wall. The inner wall of each pocket is provided of a similar shape to the outer wall, but the ridge of the outer wall is opposed by a furrow of the inner wall, and the lowest part of the furrow of the inner wall is disposed opposite to the hole or holes of the ridge of the outer wall; but the inner wall of each pocket is at the sides diverted outwardly towards the outer wall and to form a flange on each side having a flat face, so that the adjacent sections of the inner wall of the flue have a space left between them forming a continuous circular or annular slot through which gas or vapour may pass from inside the flue into the pocket and through the pocket to the outside, or vice versa; and while the hole or holes formed in the outer wall of each of the pockets permits of the finely divided material passing to some extent into the pocket, the outwardly extending flanges provided at the respective sides of the inner wall of each pocket prevent the passage of the material into the flue. Should any of the finely divided material however find its way into the flue, the inclination of the outside of the inner wall towards the circular or annular slot causes its return to the pocket on the rotation of the casing, and its passage from the pocket to the casing is caused in the manner described.

The flue may be divided into a number of sections by a diametric wall at intervals, so as thus when treating material within the casing by means of vapour or gas, the vapour may be led into one length of the flue, the vapour or gas passing thence into the casing and from the casing into the next section of the flue and so on and finally to

the outlet end of the flue. For the purpose of the end plates of the casing may be provided with an inlet and outlet pipe connection respectively with means to permit of the rotation of the casing while maintaining a gas tight joint. Furthermore radial baffle plates or ledges may be provided on the inner wall of the casing for the purpose of lifting the material to a considerable height 5 on the rotation of the casing and such baffle plates may be arranged in any manner with their faces or edges parallel with the axis of rotation or inclined or otherwise disposed.

10 The invention comprises the constructional features which are hereinafter described.

15 The invention is illustrated by way of example in the accompanying drawings in 20 which—

25 Figure 1 represents a sectional elevation with the flue partly shown in section of a rotating retort provided according to the invention.

Figure 2 is a cross section on the line 30 $x-y$ Figure 1, while

Figure 3 is a partial sectional elevation on a larger scale than indicated in Figure 1 illustrating one method of construction.

35 Figure 4 is a diagrammatic longitudinal section of a modification.

In carrying the invention into effect according to one construction as illustrated in the accompanying drawings which for example is applicable to the purpose of distillation of sawdust or other carbonaceous substance in a finely divided condition, I 40 may provide a cylindrical casing a to contain the sawdust or other carbonaceous substance to be distilled, and I may provide the necessary means for example a chain wheel b for causing the rotation of the cylindrical casing a . A pipe c is fitted to the cylinder a to carry off the vapor. The cylinder a is 45 mounted for rotation in a usual manner within any desired type of furnace. In a central axial position within the casing a I mount the flue d and this for example may be of a diameter of one-third that of the casing a , but it will be understood that the 50 relative dimensions of parts will be determined according to the particular conditions and requirements. At the rear end of the casing a the end plate e may be provided 55 with an inwardly protruding cylindrical flange e^1 for the reception of the end of the flue d and in intermediate positions arms or brackets f may be provided lying against the outer wall of the casing a for the support of the flue d in intermediate positions, while at the front end, the end plate g of the casing may be provided with a cylindrical flange g^1 forming a central aperture through which the central flue d may be introduced into the casing a or withdrawn and

60 through which admission may be had to the flue d for inspection or repair, and this central aperture may be covered by means of a removable cover plate g^2 .

65 The flue d is made up of a number of annular plates of metal h and i formed with annular flat flanges h^1 , h^3 and i^1 , each plate having a conical peripheral part. Thus the outer wall of the series of annular pockets is 70 formed of pairs i of such plates disposed back to back so that the flat annular flanges i^1 are disposed adjacent and in vertical planes and the conical peripheries are directed and flare outwardly. Each connected pair of plates h and i may be mounted 75 upon a number of parallel disposed longitudinal rods j passing through the annular flat flanges h^1 and i^1 respectively and is secured and spaced apart upon the longitudinal rods j by means of collars k , and the respective 80 plates of each pair h and i may be connected together by riveting. The respective pairs of plates h and i are spaced apart 85 so that a space or interval is left between their adjacent outer edges. One of each 90 adjacent pair of plates i serves to form the outer wall of the annular pockets. In a similar way the inner wall of the respective annular pockets is formed by two annular plates h which are riveted together by 95 rivets h^2 passing through their adjacent flat annular flanges h^3 . The respective peripheral parts of these respective pairs of plates incline inwardly to form a furrow in line 100 with the ridge and circumferential hole or slot l in the outer wall of the pocket, and the inner wall of the pocket thus formed is provided laterally with flat annular flanges h^1 which serve to carry the plates forming the inner wall upon the longitudinal rods j . 105

110 The flue d may thus be made up of a number of annular plates of concave or V shape form as illustrated. In the case of the outer series of plates i this concavity is preferably shallow. The inner series of plates h may be formed of concave or V-shaped rings of greater concavity. The back and front surfaces of the annular flanges of both series of plates may correspond, and be parallel, or again the convex surfaces may have 115 greater convexity than the concave surfaces have concavity.

120 The collars k by means of which the respective plates i forming the sections of the outer wall are secured in position upon the longitudinal rods j may serve as distance pieces to determine the space between the lateral flanges h^1 of the inner wall, and the flanges i^1 of the outer wall of the respective pockets. Any suitable number of 125 parallel disposed rods j may be used to carry and to secure together the respective series of plates h to form the flue d , and the rods j may be connected at their respective ends to the flanges m^1 of rings m . The 130

ring m at one end fits within the cylindrical flange e^1 of the end plate e of the casing a , while the ring m at the other end of the flue fits within the cylindrical flange g^1 . In 5 intermediate positions as before stated the flue thus formed may be supported by arms or brackets f from the outer casing a , these arms or brackets being connected at their ends to the rods j at intervals according to 10 the length of the flue.

In the use of the retort the sawdust or other substance to be distilled or treated may be charged into the retort casing a through the aperture o and the aperture o may then 15 be closed by a cover plate o^1 . The retort casing a is then introduced into the heating furnace and while subject to heat the retort casing a is continuously or periodically rotated.

20 In distillation the vapours produced pass through the circumferential slots l into the respective annular pockets and thence through the annular spaces between the respective flanges i^1 and h^1 and thence through 25 the fitting c^1 into the vapour discharge pipe. Any sawdust that finds access to the annular pockets in an upper position of the flue will on the rotation of the flue into a lower position pass down the wall of the plates i 30 through the slot l and any sawdust that may find access from the annular pockets into the flue through the annular spaces between the respective flanges h^1 and i^1 in an upper 35 position will in the rotation of the flue into a lower position pass down the inner face of the annular plates h back through the annular space between the flanges h^1 and i^1 and thence will ultimately pass out of the pocket 40 through the circular hole or slot l . By such means the vapours produced in the distillation find ready access into the flue and the charge in distillation notwithstanding that it is in a finely divided condition is retained within the casing.

45 The apparatus illustrated in Figures 1 to 3 of the accompanying drawings may with slight variation be used for the treatment of substances in a finely divided condition. In such a case the flue constructed as herein- 50 before described may as diagrammatically illustrated in Figure 4 be provided with diametrical partitions p carried upon the rods j and annular partitions q may be mounted within the casing in a position between the 55 partitions p and p^1 so that thus the vapour or gas passing through the end fitting c^1 at one end of the casing a may take a course

indicated by the arrows w , the vapour discharging through the end fitting c .

I claim:

1. An apparatus of the kind described comprising a casing mounted for rotary movement and having a flue extending longitudinally thereof with its axis coinciding with the axis of the flue, pockets extending 60 between the flue and the casing and having communication with both to permit of the free passage therebetween of gases, said pockets provided with inclined walls adapted to direct solid matter into the casing and 65 from entering the flue, substantially as described.

2. An apparatus of the kind described comprising a rotatably supported casing having a flue therein with its axis coincident 70 with the axis of the casing, pockets extending annularly about the flue and having communication with the interior of the casing and being further provided with circumferential slots setting up communication between the interior of the flue and the 75 pockets, said pockets provided with inclined walls for diverting solid matter into the casing and away from the circumferential slots, substantially as described.

3. An apparatus of the kind described comprising a cylindrical casing mounted for rotation, a flue disposed lengthwise of the casing, a series of annular pockets having inner and outer walls of an alternate ridge 80 and furrow section, the furrow on the outer face of the inner wall being opposite the ridge on the outer face of the outer wall, said 85 pockets having circumferential slots provided in the respective ridge parts of the inner and outer walls, substantially as described.

4. In apparatus for carrying out processes in the use of materials in a finely divided condition and in which a rotary casing is employed, a flue provided with a series of 100 annular intercepting pockets formed of metal plates having peripheral parts and flat flanges, a circular series of rods by means of which the said plates may be disposed in series to form the flue, the 105 said plates forming inner and outer walls for the flue of an alternate ridge and furrow section, the furrow on the outer face of the inner wall being opposite to the ridge on the outer face of the outer wall, said 110 respective ridge parts of the inner and outer walls having cylindrical spaces therebetween, substantially as described.

PHILIP POORE.
